US00D561792S

(12) **United States Design Patent** (10) Patent No.: **US D561,792 S**
Johnson (45) Date of Patent: **** Feb. 12, 2008**

(54) **HEAT TRANSFER MACHINE**

(75) Inventor: **Larry Johnson**, Yorba Linda, CA (US)

(73) Assignee: **Insta Graphic Systems**, Cerritos, CA (US)

(**) Term: **14 Years**

(21) Appl. No.: **29/266,606**

(22) Filed: **Sep. 25, 2006**

(51) **LOC (8) Cl. 15-99**

(52) **U.S. Cl. D15/146**

(58) **Field of Classification Search** D15/123, D15/144-146; 38/17; 100/92, 233, 300, 100/301, 315-325; 101/9, 10, 27; 156/579, 156/583.8, 583.9; 219/227, 243

See application file for complete search history.

(57) **CLAIM**

The ornamental design for a heat transfer machine, as shown and described.

DESCRIPTION

FIG. 1 is a front perspective view of the invention;

FIG. 2 is a right side view of the invention;

FIG. 3 is a rear view of the invention; and,

FIG. 4 is a bottom view of the invention.
